(57) **CLAIM**

The ornamental design for a tire as shown and described.

DESCRIPTION

FIG. 1 is a perspective view of a tire showing my new design;

FIG. 2 is a front view thereof;

FIG. 3 is a rear view thereof; and,

FIG. 4 is a side view thereof, the opposite side view being a mirror image thereof.

The drawings include shadows and reflections which indicate contour, not surface ornamentation.

The claimed design exhibits rotational symmetry.
